DIAL INDICATOR

James G. Sisson, Athol, Mass., assignor to The
L. S. Starrett Company, Athol, Mass., a corpora-
tion of Massachusetts

Application October 8, 1934, Serial No. 747,403

3 Claims. (Cl. 116—129)

My present invention relates to certain improvements in adjustable dial indicators and particularly to such indicator constructions as include locking mechanism for the bezel ring. Such locks have been produced heretofore in a great variety of forms of which those of the external clamping type are quite old in the art and satisfactory for some indicators and under some circumstances. Such external clamping devices, however, are open to certain objections, particularly where the clamp piece is in an exposed position on the exterior of the indicator casing.

My present invention provides for bezel locks which may be of the built-in-type and so positioned and contained within the wall of the casing as to be protected thereby. Moreover, according to my invention I am able to do this without material addition of cost over the older external clamping locks.

As illustrative of my invention I have shown an indicator construction including such bezel lock together with certain modifications or variants of the same. These appear in the accompanying drawing as follows:—

Fig. 1 is a partly sectioned view of an indicator of a type in accordance with my invention.

Fig. 2 is a fragmentary view partly in section through the locking mechanism of such an indicator.

Fig. 3 is a fragmentary section of a modified form of lock, and

Fig. 4 is a section through the lock portion of a further modified form of indicator in accordance with my invention.

In this drawing I have shown an indicator construction in which the casing consists of a cylindrical shell 1 the exterior of which is uninterrupted save for the exterior opposite spindle bearings 10 and 11 of the contact rod or feeler 13, the former being tightly closed by a dust cap 12.

Such a shell 1 is of sufficient thickness to be recessed or rabbeted as at 11 at its front and rear edges to receive a back plate 2 and a front plate 3. This plate 3 carries the bridge piece and the bearings for the internal parts and constitutes a front closure for the shell 1.

Rotatably mounted on the front edge of the shell 1 is a knurled bezel ring 5 carrying the usual dial and transparent protective bezel. The inner face of the ring 5 is channeled as at 15 and so overlies the front edge of the casing 1 in the plane of the front plate 3.

The inner face of the casing 1 is transversely grooved as at 16 to receive a locking piece 14. At its outer end the piece 14 has an upturned

foot 14¹. This footed end projects through an opening 3^a in the edge of the front plate 3 and thus is properly held and guided.

The edge 1¹ of the casing 1 is notched as at 1^a to receive the foot 14¹ and support and guide it in its relation to the channel 15 of the bezel ring 5 for which it acts both as a lock and a keeper.

Such a lock is preferably controlled by a threaded clamping member. In the form shown in Fig. 2 a headed stud 17 passes through the block 14 and the casing 1 being threaded at its outer portion to receive the bezel clamp nut 18. This may be loosened to free or unlock the bezel or tightened to draw up on the lock piece 14 and push the edge of its upturned foot 14¹ radially 15 outward against the bottom wall of the bezel groove 15 and thus hold the bezel against rotation. As the footed lock piece 14 and the upturned foot 14¹ are guided and supported in the notches 1^a and 3^a the foot acts as a broad steady keeper for holding the bezel ring 5 in its rotatable assembly on the edge of the casing 1.

In the modified form shown in Fig. 3, the parts are essentially the same but the lock piece 24 is tapped to receive the threaded end 27 of a shouleder clamp screw 28 which draws up on the clamp and forces its footed end 24¹ against the bottom wall of the groove 15 of a bezel ring 5 as before described.

In both of these forms the exposed surface of the casing 1 is imperforate except for the clamp screw hole which is covered by the nut 18 (Fig. 2) or the head 28 (Fig. 3) so that there are no external channels, blocks, guide pins or other interruptions to the surface of the case 1. This is of great advantage and in contrast to the modification shown in Fig. 4 in which the case 1 has its surface recessed as at 30 to receive a slide clamp 34 having a short upturned foot 34¹ which is engaged in the groove of the bezel ring 5. The clamp 34 has a beveled opening 35 in which the beveled shoulder 38¹ of a screw 38 bears. As the threaded portion 37 is screwed in or out the beveled shoulder 38¹ crowds the slide 34 in one direction or the other forcing the foot 34¹ against the side wall of the interior groove of a bezel ring 5.

By making the locking piece flush with the casing surface and with as close a fit as is consistent with its locking movement most of the objectionable features of the old outside locks are avoided and the qualities of the inside lock approximated.

I am aware that in the prior art it has been proposed to clamp a bezel ring by contact with

its inner face. I am also aware that the old bezels usually had inner grooves for engagement by a screw, or stud or catch to hold the bezel in assembly and I do not therefore claim such broadly but I am not aware of any prior indicator in which an internal bezel lock was provided to engage such a bezel inner groove and thus serve as both lock and keeper, or constructed and embodied in such an indicator combination as I have herein shown and described.

What I therefore claim and desire to secure by Letters Patent is:—

1. In a dial gage, a cylindrical casing, a front plate and a back plate in the ends of said casing, a bezel rotatably mounted on the front edge of the casing cylinder and overlying the front plate, said bezel having an internal groove adjacent the casing edge, said casing and front plate having a transverse interior recess, a locking piece guided in said recess, threaded adjusting means for the locking piece disposed through the casing and having an operating portion externally thereof, said locking piece having at its end a clamping foot disposed through the casing edge and having its end within the bezel groove for radial outward contact with the groove bottom when the bezel is to be clamped in place.
2. In a dial gage, a cylindrical casing, a front plate and a back plate in the ends of said casing, a bezel rotatably mounted on the front edge of

the casing cylinder and overlying the front plate, said bezel having an internal groove adjacent the casing edge, said casing having a transverse interior recess and a radial opening from said recess through the casing edge, a locking piece guided in said recess, threaded adjusting means for the locking piece disposed through the casing and having an operating portion externally thereof, said front plate having an opening communicating with said slot, said locking piece having at its end a clamping foot disposed through said radial opening in the casing edge and having its end within the bezel groove for clamping contact with the groove bottom when the bezel is to be clamped in place.

3. In a dial gage, a cylindrical casing, a bezel rotatably mounted on the front edge of the casing cylinder, said bezel having an internal groove adjacent the casing edge, said casing having a transverse interior recess on its inner surface, a locking piece guided in said recess, threaded adjusting means for the locking piece disposed through the casing and having an operating portion externally thereof, said locking piece having at its end a clamping foot and having its end within the bezel groove for radial outward contact with the groove bottom when the bezel is to be clamped in place.
